(57) **CLAIM**

The ornamental design for a rotor for electric motor, as shown and described.

DESCRIPTION

FIG. 1 is a perspective view of a rotor for electric motor showing my new design;

FIG. 2 is a front view thereof;

FIG. 3 is a rear view thereof;

FIG. 4 is a right side view thereof; a left side view being a mirror image;

FIG. 5 is a top view thereof; a bottom view being a mirror image;

FIG. 6 is a cross-sectional view of 6-6 lines in FIG. 2 thereof;

FIG. 7 is a cross-sectional view of 7-7 lines in FIG. 2 thereof;

FIG. 8 is a cross-sectional view of 8-8 lines in FIG. 2 thereof; and,

FIG. 9 is an enlarged view of 9-9 lines in FIG. 2 thereof. The broken lines in the drawings illustrate portions of the rotor for electric motor which form no part of the claimed design.
